DESIGN.

—o—

A. B. CAMERON.

PANEL.

No. 20,366.

Patented Dec. 9, 1890.

UNITED STATES PATENT OFFICE.

ALLAN B. CAMERON, OF WILLIAMSPORT, PENNSYLVANIA.

DESIGN FOR A PANEL.

SPECIFICATION forming part of Design No. 20,366, dated December 9, 1890.

Application filed November 12, 1889. Serial No. 330,077. Term of patent 14 years.

To all whom it may concern:

Be it known that I, ALLAN B. CAMERON, of Williamsport, Lycoming county, Pennsylvania, have invented and produced a new and original Design for Panels, of which the following is a specification, reference being had to the accompanying photograph, forming part hereof.

Upon the surface of the panel appears a rectangular elevation A, and upon said elevation and extending from the center B thereof appear numerous channels or grooves C, which terminate at the edge of said elevation A. The elevation A thus appears to be di-

vided into a number of triangular elevations ¹⁵ having their apexes meeting. Each of the triangular elevations shows stepped edges, as indicated at C. At the center of the elevation A may appear an ornamental circular button E.

I claim—

The design for an ornamental panel, substantially as herein shown and described.

ALLAN B. CAMERON.
